[57] CLAIM

The ornamental design for a diver's mask, as shown and
described.

DESCRIPTION

FIG. 1 is a front and top perspective view of a diver's
mask showing my new design;

FIG. 2 is a front elevational view thereof;

FIG. 3 is a rear elevational view thereof;

FIG. 4 is a side elevational view thereof, the opposite
side view being a mirror image of that shown;

FIG. 5 is a top plan view thereof; and

FIG. 6 is a bottom plan view thereof.

FIG.1

FIG.2

FIG.3

FIG.4
